UNITED STATES PATENT OFFICE.

HOMER F. CATES, OF KANSAS CITY, MISSOURI, ASSIGNOR OF ONE-HALF TO JOHN H. RICHA, OF KANSAS CITY, MISSOURI.

DETACHABLE STORM-COLLAR FOR COATS.

1,160,378.

Specification of Letters Patent. Patented Nov. 16, 1915.

Application filed November 15, 1913. Serial No. 801,173.

To all whom it may concern:

Be it known that I, HOMER F. CATES, a citizen of the United States, residing at Kansas City, in the county of Jackson and State of Missouri, have invented certain new and useful Improvements in Detachable Storm-Collars for Coats, of which the following is a specification.

My invention relates to improvements in detachable storm collars for coats.

My invention further provides a coat having a detachable storm collar and provided with means for being releasably secured thereto.

15 The object of my invention is to provide a coat with a storm collar which may be used in stormy weather, and which may be detached from the coat in pleasant weather.

A further object of my invention is to 20 provide a detachable storm collar which, when attached to a coat will conceal the ordinary coat collar and lapels, and which when so attached will present the appearance of a collar which has been built up 25 with the body of the coat, and which may be turned up or folded down in the manner of the ordinary collar and lapels.

A further object of my invention is to 30 provide a storm collar which may be sold separately and attached to coats which are already in use.

Other novel features of my invention are hereinafter described and claimed.

In the accompanying drawings which 35 illustrate the preferred embodiment of my invention, Figure 1 is a front elevation of a coat having attached thereto a storm collar of my invention, the latter being shown turned down and partly broken away. Fig. 40 2 is a side elevation of a coat provided with my improvement, the storm collar being shown turned up. Fig. 3 is an end view of the storm collar shown stretched out, a part of one side of the pocket being turned 45 upwardly, to disclose the securing means on the inner side thereof. Fig. 4 is an enlarged vertical section on the line *a*—*b* of Fig. 2. Fig. 5 is an enlarged vertical central sectional view, showing the storm collar and 50 coat collar turned down.

Similar reference characters designate similar parts in the different views.

1 designates the body of an ordinary coat adapted to be worn by a man or woman; 2

designates the coat collar, and 3 the lapels 55 of the coat.

4 designates an arcuate detachable storm collar, preferably of flexible material, such as woolen cloth, said cloth being worn so as to provide a pocket 5 which extends nearly 60 the entire length of the storm collar and is adapted to receive therein the coat collar 2 and the lapels 3. In order that the storm collar may be reliably held in its proper position on the coat, it is, preferably, provided with means by which it may be releasably secured to the coat. For this purpose I preferably provide ordinary glove fastening devices 6 which as shown in Fig. 3, 65 are secured to opposite inner sides of the 70 storm collar, and which are adapted to releasably engage glove fastening devices 7 which are provided on the inner sides of the coat collar 2 and of the lapels 3, and on the inner side of the body of the coat below 75 the top of the coat collar. By having the fastenings 7 located on the inner side of the body of the coat and in the inner sides of the coat collar and lapels, these fastenings will not be visible when the storm 80 collar is removed and the coat collar and lapels are turned down to the position shown in Fig. 1. As shown in Fig. 3 one side of the storm collar is wider than the opposite side and extends below the pocket 5. 85

In applying the storm collar to the coat the collar 2 and lapels 3 are slipped into the pocket 5 with the wide side of the storm collar disposed toward the front of the coat and having its securing devices 6 attached 90 to the securing devices 7 which are located on the inner side of the body 1 of the coat, as shown in Fig. 4. The narrow side of the collar is disposed at the rear of the coat collar when the latter is turned up as in Fig. 4, 95 and has its securing devices 6 secured to the securing devices 7 which are located on the inner sides of the coat collar and lapels. When the coat collar 2 is turned down to the position shown in Figs. 1 and 5, the storm 100 collar 4 will be folded over the upper end of the body 1 of the coat. In either of the positions shown in Fig. 4 and Fig. 5 the securing devices 6 and 7 will be hidden by the storm collar and the storm collar and 105 coat will present the appearance of being built up instead of being detachably connected to each other. When the storm col-

lar has been thus secured to the coat it will completely hide the coat collar and lapels and will not interfere with the buttoning of the coat.

5 I do not limit my invention to the structure shown and described, as modifications, within the scope of the appended claim, may be made without departing from the spirit of my invention.

10 Having thus described my invention, what I claim and desire to secure by Letters Patent, is:—

15 A coat having a collar and lapels, securing means invisible from the exterior on the inner side of the coat and upon the inner side

of the collar and lapels, and a detachable storm collar provided with a pocket adapted to receive the coat collar and lapels, opposite inner sides of the pocket being provided with securing means invisible from the exterior and respectively engaging said securing means which are on the inner side of the coat, collar and lapels. 20

In testimony whereof I have signed my name to this specification in presence of two 25 subscribing witnesses.

HOMER F. CATES.
